ELEVATOR

Arnold Redler, Stroud, England, assignor to Redler Conveyor Company, Quincy, Mass., a corporation of Massachusetts

Application August 2, 1940, Serial No. 349,665
In Great Britain August 23, 1939

11 Claims. (Cl. 198—126)

This invention relates to an elevator and more particularly to an elevator for withdrawing and discharging material from the hold of a ship or other source of supply.

The invention has for an object to provide a novel and improved elevator of the character specified in which provision is made for supporting the structure in a manner such as to enable the elevator to automatically lower itself into the material being discharged in accordance with the level of the material as the transference proceeds and which is of a simplified construction of the unit and may be operated with minimum labor.

With this general object in view and such others as may hereinafter appear, the invention consists in the elevator and in the various structures, arrangements and combinations of parts hereinafter described and particularly defined in the claims at the end of this specification.

In the drawing illustrating the preferred embodiment of the invention, the figure represents an elevator arranged to withdraw material from the hold of a ship and to discharge the material into a car disposed alongside of the ship.

According to the present invention, an elevator adapted to elevate material from a hold or other source of supply is arranged to be raised and lowered as a unit, the weight of the conveyor being substantially borne by a counterbalance or equivalent device whereby the elevator can be manipulated by manual labor without the necessity of permanently employing a crane or equivalent to keep the elevator in the most advantageous position for feeding. The invention may be applied to conveyors of all kinds including those in which a tubular casing accommodates one or more endless chains fitted with a series of transverse flight members, which latter may be solid plates, semi-solid flights or skeleton frames, and which may be arranged normal to the run of the chain or chains or inclined forwards or rearwards in relation thereto. It is also applicable to other kinds, including those of the suction type, an essential requirement being a casing or conduit having an opening at or adjacent the bottom, through which the grain or equivalent passes and is thence raised and delivered to an elevated position.

Thus there is provided a discharger for discharging free flowing materials, which is furnished with skeleton and/or semi-solid and/or solid flights inclined or otherwise and provided with open bottom for gravitating itself into the material and also provided with an outlet de-

livery through a flexible telescopic or open spout or other suitable delivery and situated any desired distance above the bottom, the invention being characterized in that the discharger is 5 slung from a jib or other suitable means by a chain or other flexible means with a counterbalance weight which may be of approximately the same weight as the discharger, so that the latter can be raised or lowered into a barge without the usual lifting forces being necessary.

If desired the elevator or discharger may be so arranged with its counterbalancing means, that the weight of the upwardly carried material has the effect of maintaining the elevator or discharger in contact with the material in the hold or source of supply, or even to penetrate the material of its own accord. This enables the unloading process to take place in a semi-automatic manner, the elevator or discharger following the 10 level of the material as the latter falls. Moreover, if manual manipulation is required, a relatively light force is sufficient to move the elevator or discharger bodily. When the upward flow of the material ceases the effective weight of 15 the device is decreased thus enabling the elevator or discharger to move upwards of its own accord or by a minimum of manual effort or that of a relatively light hoist.

Automatic means, conveniently in the form of 20 one or more receptacles each fed with material and arranged to empty itself, may be incorporated to secure an automatic lifting and falling of the elevator or discharger, depending upon the flow of material being lifted.

35 In one arrangement according to the invention, an endless chain elevator disposed within a casing of inverted U-shape, with an opening at the bottom and an outlet at the top, is suspended as a unit from one extremity of a lever 40 which is pivoted intermediate its ends to a hoist or other supporting device. At its other end, the lever is provided with a counterweight and the whole elevator is arranged to swing about the supporting device to permit the mouth of the 45 elevator to be positioned as desired, the weight of the counterbalance being such that when the elevator is inoperative, the latter is held in suspension or even tends to rise.

A receptacle having a discharge opening is 50 attached to the elevator, and when the installation is working, receives a part of the material so that the weight of the elevator is increased and the latter tends to press downwards into the body of the material. Shortly after the elevating process ceases, the receptacle becomes empty

and the consequent reduction in the weight of the elevator causes the latter to be lifted by the counterweight. In an alternative arrangement, the receptacle is connected operatively with the counterweight by a lever or other mechanism so that the weight of said receptacle and its contents opposes the downward force of the counterweight. The receptacle is fed with material from the discharge aperture of the conveyor so that while the installation is in operation, the downward force of the counterweight is reduced by the weight of the receptacle and its contents. Thus the elevator has more of its weight available to penetrate into the material in the barge.

The principal advantage of the invention is that, in the case of unloading material from a barge, the man aboard the barge can control the discharger without the necessity of employing hoist men ashore, and the work of discharging the material thus becomes almost or entirely automatic.

Referring now to the drawing, 10 represents an elevator of the self-loading loop boot type comprising a casing 12 and an endless conveying element 14 arranged to be drawn through the casing to effect the conveyance of the material therethrough. The casing is provided with an opening 16 in the bottom through which the material enters when the lower portion of the unit is buried in the material and also a discharge outlet 18 disposed any desired distance above the bottom and provided with a flexible delivery chute 20.

The conveying element 14 may comprise an endless chain provided with a plurality of spaced transverse flight members 22 of any usual construction such as solid flights or the open type skeleton frame flights. The conveying element is arranged to pass over a driving sprocket 24 at the upper portion of the conveyor and the sprocket may be driven through connections from an electric motor 26 supported on the elevator and which may be controlled by a push button switch arranged below in any convenient position.

As illustrated herein, the elevator 10 is suspended from one end of a lever 28 which may be pivoted intermediate its ends at 30 to a hoist or other supporting device indicated generally at 32 and, at the other end, the lever is provided with a counterweight 34, the weight of the counterweight being such that when the elevator is inoperative, the latter is held in suspension or even tends to rise. In this manner, the elevator can be raised or lowered into the barge with a minimum of manual effort.

From the description thus far, it will be observed that in operation, when the elevator is loaded with material, the effect of this extra weight will be to cause the elevator to lower itself and to penetrate into the material being withdrawn in accordance with the level thereof as the transference proceeds, and that when the material is depleted, the empty elevator will move upwardly of its own accord.

In the preferred embodiment of the invention, as herein shown, a receptacle 36 may be attached to the elevator in a position to receive a portion of the load being discharged in order to further increase the weight of the elevator during the discharging operation. The receptacle 36 may have a relatively large inlet 38 disposed adjacent the discharge outlet 18. The bottom of the receptacle may be provided with a small opening 40 through which the material may be slowly

drained. When the elevating operation is completed, the receptacle becomes empty and, as hereinbefore described, the consequent reduction in weight of the elevator causes the latter to be lifted by the counterweight 34.

While the preferred embodiment of the invention has been herein illustrated and described, it will be understood that the invention may be embodied in other forms within the scope of the following claims.

Having thus described the invention, what is claimed is:

1. In a device of the character described, in combination, an elevator comprising a casing having an inlet at its lower end engageable with the material to be discharged and having an outlet adjacent its upper end, and means for suspending the elevator above the material including a counterweight operatively connected to said elevator for counterbalancing the weight thereof, and a receptacle arranged to receive a portion of the material being discharged, the weight of which material will effect a downward movement of said elevator to cause the latter to descend in accordance with the level of the material being discharged.

2. In a device of the character described, in combination, an elevator comprising a casing having an inlet at its lower end engageable with the material to be discharged and having an outlet adjacent its upper end, and means for suspending the elevator above the material including a counterweight operatively connected to said elevator for counterbalancing the weight thereof, and a receptacle arranged to receive a portion of the material being discharged, the weight of which material will effect a downward movement of said elevator to cause the latter to descend in accordance with the level of the material being discharged, said receptacle having a relatively small opening at its lower end through which the material may escape to permit the elevator to rise upon the termination of the discharging operation.

3. In a device of the character described, in combination, an elevator comprising a casing having an inlet at its lower end engageable with the material to be discharged and having an outlet adjacent its upper end, an endless conveying element having a plurality of spaced transverse flights traversable through the casing to effect the conveyance of the material therethrough, and means for suspending the elevator above the material including a counterweight operatively connected to said elevator for counterbalancing the weight thereof, and a receptacle arranged to receive a portion of the material being discharged, the weight of which material will effect a downward movement of said elevator to cause the latter to descend in accordance with the level of the material being discharged, said receptacle having a relatively small opening at its lower end through which the material may escape to permit the elevator to rise upon the termination of the discharging operation.

4. In a device of the character described, in combination, an elevator comprising a casing having an inlet at its lower end engageable with the material to be discharged and having an outlet adjacent its upper end, means for supporting the elevator above the material including a pivotally mounted lever, means for suspending the elevator at one end of the lever, and a counterweight suspended from the other end, and a

receptacle arranged to receive a portion of the material being discharged, the weight of which material will effect a downward movement of said elevator to cause the latter to descend in accordance with the level of the material being discharged.

5. In a device of the character described, in combination, an elevator comprising a casing having an inlet at its lower end engageable with the material to be discharged and having an outlet adjacent its upper end, means for supporting the elevator above the material including a pivotally mounted lever, means for suspending the elevator at one end of the lever, and a counterweight suspended from the other end, and a receptacle arranged to receive a portion of the material being discharged, the weight of which material will effect a downward movement of said elevator to cause the latter to descend in accordance with the level of the material being discharged, said receptacle having a relatively small opening at its lower end through which the material may escape to permit the elevator to rise upon the termination of the discharging operation.

6. In a device of the character described, in combination, an elevator comprising a casing having an inlet and an outlet, overhead means including a flexible supporting member for suspending the elevator above the material to be discharged, said suspending means permitting freedom of movement of said elevator laterally, and means for counterbalancing the weight of said elevator and operative to control the movement of the elevator vertically, and a receptacle attached to said casing and arranged to receive a portion of the material being discharged to effect a downward movement of the casing during operation of the device.

7. In a device of the character described, in combination, an elevator comprising a casing having an inlet at its lower end engageable with the material to be discharged and having an outlet adjacent its upper end, overhead means including a flexible supporting member for portably suspending the elevator above the material to be discharged, said suspending means permitting freedom of movement of said elevator laterally, and means including a counterweight for counterbalancing the weight of said elevator and operative to control the movement of the elevator vertically, and a receptacle attached to said casing and arranged to receive a portion of the material being discharged to effect a downward movement of the casing during operation of the device.

8. In a device of the character described, in combination, an elevator comprising a casing having an inlet at its lower end engageable with the material to be discharged and having an outlet adjacent its upper end, overhead means including a flexible supporting member for portably suspending the elevator above the material to be discharged, said suspending means permitting freedom of movement of said elevator laterally, and means including a counterweight for counterbalancing the weight of said elevator and operative to control the movement of the elevator vertically, and a receptacle attached to said casing and arranged to receive a portion of the material being discharged, the relation between the weight of said elevator and said counterweight being such as to effect a downward movement of

said elevator when said receptacle is supplied with material.

9. In a device of the character described, in combination, an elevator comprising a casing having an inlet at its lower end engageable with the material to be discharged and having an outlet at its upper end, an endless conveying element having a plurality of spaced transverse flights traversable through the casing to effect the conveyance of material therethrough, overhead means for portably suspending the elevator above the material to be discharged, said suspending means permitting freedom of movement of said elevator laterally, and means for counterbalancing the weight of said elevator and operative to control the movement of the elevator vertically, and a receptacle attached to said casing and arranged to receive a portion of the material being discharged, the relation between the weight of said elevator and said counterbalancing means being such as to effect a downward movement of the elevator into the material when said receptacle is supplied with material, said receptacle having provision for continuously releasing its contents whereby to cause the elevator to rise when the receptacle is empty.

10. In a device of the character described, in combination, an elevator comprising a casing having an inlet at its lower end engageable with the material to be discharged and having an outlet adjacent its upper end, overhead means including a flexible supporting member for portably suspending the elevator above the material to be discharged, said suspending means permitting freedom of movement of said elevator laterally, and means for controlling the vertical movement of said elevator, said last named means including a pivotally mounted lever attached at its pivotal point to said overhead supporting member, means for suspending the elevator at one end of the lever, and a counterweight carried by the other end of the lever, and a receptacle arranged to receive a portion of the material being discharged, the relation between the weight of said elevator and said counterweight being such as to effect a downward movement of said elevator when said receptacle is supplied with material.

11. In a device of the character described, in combination, an elevator comprising a casing having an inlet at its lower end engageable with the material to be discharged and having an outlet adjacent its upper end, an endless conveying element having a plurality of spaced transverse flights traversable through the casing to effect the conveyance of the material therethrough, overhead means for portably suspending the elevator above the material to be discharged, said suspending means permitting freedom of movement of said elevator laterally, and means for controlling the vertical movement of said elevator, said last named means including a pivotally mounted lever attached at its pivotal point to said overhead supporting member, means for suspending the elevator at one end of the lever, and a counterweight carried by the other end of the lever, and a receptacle arranged to receive a portion of the material being discharged, the relation between the weight of said elevator and said counterweight being such as to effect a downward movement of said elevator when said receptacle is supplied with material.

ARNOLD REDLER.
